Primary Examiner — Susan Bennett Hattan*Assistant Examiner* — Marie Fast Horse(74) *Attorney, Agent, or Firm* — NSIP Law(57) **CLAIM**

We claim the ornamental design for a telephone, as shown and described.

DESCRIPTION

FIG. 1 is a front perspective view of a telephone showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another right-side view thereof, in which the telephone is provided in an alternate position, rotated 45°, clockwise, relative to FIG. 5 to illustrate another embodiment;

FIG. 9 is another front view thereof, in which a portable terminal in broken lines is provided to illustrate an example environment; and,

FIG. 10 is another front view thereof, in which a module in broken lines is provided to illustrate another example environment.

The broken lines in the figures show portions of the telephone which form no part of the claimed design.

The broken line showing of the portable terminal in FIG. 9 and the module in FIG. 10 is for environmental purposes only and forms no part of the claimed design.
